UNITED STATES PATENT OFFICE

104,414

DESIGN FOR A PERFUME BOTTLE OR SIMILAR ARTICLE

Joseph S. Stein, Chicago, Ill., assignor to Lucien Lelong, Inc., Chicago, Ill., a corporation of Illinois

Application December 11, 1936, Serial No. 66,473

Term of patent 7 years

To all whom it may concern:

Be it known that I, Joseph S. Stein, a citizen of the United States and a resident of the city of Chicago, in the county of Cook and State of Illinois, have invented a new, original, and ornamental Design for a Perfume Bottle or Similar Article, of which the following is a specification, reference being had to the accompanying drawing forming a part thereof.

On the drawing:

I claim:

The ornamental design for a perfume bottle or similar article as shown.

JOSEPH S. STEIN.
